Attorney.

UNITED STATES PATENT OFFICE.

HARVEY C. WHEELER, OF LEXINGTON, MASSACHUSETTS.

TOWEL CABINET.

1,418,219.

Specification of Letters Patent. Patented May 30, 1922.

Application filed January 28, 1921. Serial No. 440,771.

To all whom it may concern:

Be it known that I, HARVEY C. WHEELER, a citizen of the United States, and a resident of Lexington, in the county of Middlesex 5 and Commonwealth of Massachusetts, have invented certain new and useful Improvements in Towel Cabinets, of which the following is a full, clear, and exact specification.

10 The object of this invention is the construction of a towel-holding case wherein an elongated towel is unwound from one spindle and wound up on a second to conceal its used portion and to present a fresh portion, the spindles being adapted for ready 15 detachment and reapplication for permitting a clean length of towelling to be substituted for one which has been used.

15 In the drawings forming part of this specification, Fig. 1 is a side view of a towel cabinet embodying my improvement, one of the actuating knobs being represented as cut off. Fig. 2 is a side sectional elevation of the same. Fig. 3 is a side view of the 20 cabinet showing the spindles being removed. Fig. 4 is a front sectional view on the line 4—4 in Fig. 1. Fig. 5 is a detailed view of 25 another form of actuating device.

The towel cabinet comprises a back 1, 30 sides 2, top 3, bottom 4, one or two shelves 5, two spindles 6 rotatable in the sides 2, and a length of towelling 7 attached at its ends to the spindles 6, and substantially all 35 wound upon one spindle when supplied in a clean condition.

The spindles 6 are preferably square or otherwise polygonal in cross section for the better retention of the towelling, for by thus being polygonal, it is only necessary to 40 give one or two winds of the fabric thereon in order to hold the same with practical security. Each spindle is provided with an actuating knob 9 at one end, having a neck 10 between it and the remainder of the spindle, and its other end is reduced to turn in a hole 11 in a side of the case.

In the right hand side 2, as we face the case, is formed a bearing for the neck 10 of each spindle, each bearing consisting of two 50 holes 13, 14 cut into each other but of unequal diameters, the hole 13 being of a size to fit the neck 10, and the hole 14 being large enough to receive the knob 9 and the spindle itself.

55 These bearings are so disposed that the

ridge 15 which partially separates the two holes, is below their centers in the upper bearing, and above their centers in the lower bearing. By means of this, the pull of the towel on the spindles does not draw the 60 necks 10 out into the large holes 14.

Further to aid in keeping the spindles in place, but even more for the purpose of preventing the towelling from unwinding too easily, a spring 16 is attached to the interior 65 of the side 2 and arranged to press upon each spindle.

In use, I prefer to locate the fresh towelling upon the lower spindle, the upper end of the towelling being attached to the upper 70 spindle, with the length between the spindles stretched substantially taut, as indicated in Fig. 2. To use the towel, the normally vertical section is drawn forward, unwinding from the lower spindle, until 75 enough thereof is in hand for convenient use. As soon as the hands or face or both have been suitably wiped, the upper spindle is turned by the application of the hand to its knob 9, until the soiled section of the 80 towel is wound thereon and only a fresh section is in sight.

When all the towelling has become soiled and wound upon the upper spindle, the latter is removed by pressing its neck 10 upward and forward into the larger hole 14, 85 against the action of the spring 16. Then the spindle end is pushed through the hole 14 far enough to withdraw its reduced end from the hole 11, and to permit such end to 90 be swung forward beyond the front edge of the side 2. This being done, the knob 9 can be withdrawn through the hole 14 and the spindle and towelling entirely removed.

In like manner, the lower spindle can be 95 removed from the case, if the end of the towel is fastened thereto as is often preferable.

In place of the knobs 9, a crank arm 17 bent up from metal rod can be used, a part 100 serving instead of the neck 10 and inserted into the end of the spindle and fastened therein, as shown in Fig. 5. This crank arm can be withdrawn through the hole 14 nearly as easily as the knob, by suitably 105 swinging and turning the spindle to allow the sections thereof to pass through the hole.

It is, of course, readily seen that the case need not have its sides 2 cut away, but their front edges can be straight, and a door 110

hinged thereto for the protection of the toweling from dust, and, if desired, a mirror can be attached to such door.

What I claim is:

- 5 1. A towel cabinet comprising a case having sides, spindles revolvably supported in said sides, and a length of toweling terminally attached to said spindles and designed to be wound thereon, each spindle having a 10 reduced portion at one end and a neck at its other end, and turning means connected with said neck exterior to the case, one of said sides having holes revolvably receiving said reduced ends, and the other side having 15 two holes for each spindle, one of which holes fits the said neck and the other of which loosely receives both an end of the spindle and the turning means, each small

hole opening into its associated large hole, but none of the holes cutting through to the 20 front edge of the cabinet sides.

2. A towel cabinet comprising a case having sides, spindles revolvably supported in said sides, and a length of toweling terminally attached to said spindles and designed 25 to be wound thereon, the supporting means for each spindle embracing a large hole and a small hole opening into each other, each spindle having a neck fitting the associated small hole, and a knob carried by said neck 30 exterior of the side and adapted to be withdrawn from within through the large hole.

In testimony that I claim the foregoing invention, I have hereunto set my hand this 26th day of January, 1921.

HARVEY C. WHEELER.
